Nicholas S. Vadder, of Troy, N.Y.
Assignee to Eliz. A. McEwan, of same place,
Letters Patent No. 1294, dated 9th July, 1860,

The schedule referred to in these Letters Patent and making part of the same,

To all whom it may concern,

Be it known that I, N. S. Vadder, of the City of Troy,
in the County of Rensselaer, and State of New York, have invented or produced a
new and original Design for Stove plates, and I do hereby declare that the following
is a full and exact description of the same, reference being had by letters to the annexed
